UNITED STATES PATENT OFFICE.

NICHOLAS BARRY AND CLYDE ALLEN, OF MUSCATINE, IOWA.

ACETYLENE-TORCH.

1,248,994.

Specification of Letters Patent.

Patented Dec. 4, 1917.

Application filed February 28, 1917. Serial No. 151,499.

To all whom it may concern:

Be it known that we, NICHOLAS BARRY and CLYDE ALLEN, citizens of the United States, residing at Muscatine, in the county 5 of Muscatine and State of Iowa, have invented certain new and useful Improvements in Acetylene-Torches; and we hereby declare that the following is a full, clear, and exact description thereof, reference being had to the accompanying drawings, which form part of this specification.

Our invention is a novel improvement in gas torches or burners which are used in the mechanic arts for brazing, welding, soldering, cutting, and analogous purposes.

The invention particularly relates to that type of torch in which oxygen and acetylene gases are employed as the heating means. These torches have been usually made in 20 such manner that the full flame burns continuously unless the operator separately closes the valves and extinguishes the flame; which renders it necessary to repeatedly relight the torch when used intermittently, 25 and causes considerable loss of time. If the operator allows the torch to burn continuously a great waste of gas results; and frequently causes serious accidents.

The principal object of our invention is 30 to provide such a torch with means whereby the gases are under the instant control of the thumb or finger of the operator; and by simply depressing a finger lever a heating flame may be produced as and when it 35 is desired to use the torch; and when the torch is not in actual use the flame can be cut off by merely releasing such finger lever, while a pilot light will be maintained ready to ignite the flame when it is again wanted; 40 so that the operator can handle such torch with safety and use it effectively as and when he may desire.

A further object of our invention is to save the acetylene and oxygen gases by having 45 them both under the control of the operator, who can, by merely moving the thumb or finger of the hand holding the torch open or close the controlling valve means so that after an operation is performed the flame 50 can be shut off while leaving a pilot light; and this is a great advantage where the nature of the work requires intermittent use of the torch; and it also prevents injury to workmen by accidental contact with the 55 flame when the torch is not in actual useful operation; and it also protects fellowwork-

men against danger of careless handling of the torch when not in actual useful operation.

We will explain the invention in connection with the embodiment thereof illustrated 60 in the accompanying drawings in which—

Figure 1 is a side view of the complete torch.

Fig. 2 is a top plan view thereof.

Fig. 3 is an enlarged detail sectional view indicating the valve in partly closed position.

Fig. 4 is a horizontal detail sectional view of the parts shown in Fig. 3.

The invention is shown as applied to a torch having a handle 1 provided with a head 1^a in which are two gas passages 2^a and 3^a that are respectively connected at their inlet ends to pipes 2 and 3, that are in turn to be respectively connected, by suitable tubing or hose, to reservoirs of oxygen and acetylene gases, or other suitable gases used in such torches.

The outlet of the passage 2^a is connected 65 by a pipe 2^b with the burner-head or mixing chamber 4, which may be of usual or any suitable construction. The outlet of the passage 3^a is also connected with the head 4 by means of a pipe 3^b.

The passages 2^a and 3^a are controlled by suitable valve means adapted to be simultaneously operated. In the example shown a taper valve 5 extends through the head 1^a and intersects both passages 2^a and 3^a, and 70 said valve 5 is provided with two ports, 5^a and 5^b, which are adapted respectively to establish communication between the inlet and outlet ends of the passages 2^a and 3^a or to close said passages when the valve is properly adjusted.

The ports 5^a and 5^b are preferably so arranged and constructed that port 5^a will be closed after the port 5^b is closed, and will be opened before port 5^b is opened; this is 75 for the purpose of insuring that the acetylene will be admitted to the mixer and burner head 4 before the oxygen gas is admitted thereinto, and also for the purpose of enabling a small amount of acetylene to 80 be continuously supplied to the burner head 4 to maintain a pilot light at the tip of burner head 4 when the oxygen gas is cut off.

The valve 5 is provided with a controlling 85 lever or handle 5^c having a thumb or finger piece 5^d on its outer end that is formed to lie

in a convenient position to be depressed by the thumb or finger of the hand of the workman grasping the handle 1 of the torch. The valve may be closed, or normally returned to 5 closed position, by suitably arranged spring means; in the drawings a helical spring 8 is shown as connected to the projecting end of the valve and to the casing.

The head 1^a of the handle, is preferably 10 provided with lugs 1^d and 1^e projecting on opposite sides of the lever 5^e and through said lugs 1^d and 1^e are tapped, screws 6 and 7 which serve as adjustable stops to limit the throw of the lever 5^e and consequently 15 the extent of rocking movement of the valve 5. The extent of rocking movement of the valve is regulable by adjusting stops 6 and 7. The stop 6 should be so adjusted that when the finger piece 5^f is engaged the spring will cause the valve to 20 shut off the oxygen gas and partly shut off the acetylene gas, but permit enough acetylene, or other suitable gas, to pass to the mixing head 4 to support a pilot light at tip 25 of head 4. The stop 7 should be adjusted to such position that when the finger piece 5^f is depressed the valve is turned so as to admit the proper amount of oxygen and acetylene gases, or other suitable gases, to the 30 mixer-head 4 to produce the desired operative flame.

Operation.

The torch should first be properly connected with suitable gas supplies. Then 35 when the operator desires to use the torch the pilot flame should be ignited at tip of the head 4; and when he is ready to apply the flame he depresses finger piece 5^f with 40 the thumb or finger of his hand holding the torch; thereby operating the valve 5 and opening both passages 2^a and 3^a and admitting the proper supply of oxygen and acetylene or other suitable gases to flow to the 45 head 4, and produce the working flame; and this flame is continued so long as he depresses the finger piece 5^f. If he desires to inspect the work, or upon completion of the work, he can release lever 5^e by moving his 50 finger or thumb without letting go of the handle; thereupon the gas will be shut off, except such as is required for the pilot light. When the workman wants to again use the torch he simply depresses the finger piece 5^f and immediately the service flame is produced.

With such a torch there is no danger of the workman injuring himself or adjacent workmen by carelessly handling the torch 60 when the flame is on, as is the case with the present commonly used burners or torches and such torch greatly economizes gas, facilitates working operations, and obviates a great deal of the danger heretofore attendant upon the use of such torches.

What we claim is:

1. A torch, having a handle provided with passages for acetylene and oxygen gases, a mixer head, pipes connecting the outlets of said passages with the mixer head, 70 and means for conducting suitable gases to the inlet of said passages, valve means intersecting said passages having ports adapted to communicate therewith, a spring for closing the valve, a finger lever connected with 75 said valve for opening same when pressed by the finger, and means for limiting the movement of the valve whereby when the valve is depressed the full flame is on and when the valve is released the pilot light is 80 maintained in the mixer head.

2. In a torch the combination of a handle, a mixer head, means for directing gases through the handle to the mixer head, valve means on the handle controlling the supply 85 of gases; a thumb lever and connections for opening the valve when the lever is depressed, and means for automatically closing the valve when the thumb lever is released; with stops for limiting the opening 90 and closing movements of the valve means whereby a full flame is maintained when the said lever is depressed; and a pilot light maintained when the lever is released.

3. A torch, adapted to be held in the 95 hand, having a handle provided with gas passages, means for supplying gases to said passages, a mixer, pipes connecting the mixer with the passages, valve means controlling the flow of gases through the passages, a valve controlling lever adapted to be operated by the finger to open the said passages when the lever is depressed, and spring means for closing the valve means when the lever is released; with stops for 100 limiting the opening and closing movements of the valve means whereby a full flame is maintained when the said lever is depressed; and a pilot light maintained when the lever is released.

4. A torch having a handle provided with passages for acetylene and oxygen gases, a mixer head, pipes connecting the outlets of said passages with the mixer head, and means for conducting suitable gases to the 115 inlet of said passages, a valve intersecting said passages having ports adapted to communicate therewith, a spring for closing the valve, a finger lever connected with said valve for opening same when pressed by the 120 finger, lugs attached to the handle and projecting at opposite sides of the lever, and limiting stops tapped through said lugs for the purpose of regulating the extent of movement of said lever, substantially as described.

5. A torch having a handle provided with a head having passages for acetylene and oxygen gases, a mixer head, pipes connecting the outlets of said passages with the 130

mixer head, and means for conducting suitable gases to the inlet of said passages, a valve intersecting said passages having ports adapted to communicate therewith, a 5 spring for closing the valve, a finger lever connected with said valve for opening same when pressed by the finger, lugs on the handle head at opposite sides of said lever and limiting screws tapped through said lugs 10 for regulating the extent of movement of

said lever; whereby when the lever is depressed the full flame is on, and said ports arranged and constructed so that when the lever is released a pilot light is maintained in the mixer head. 15

In testimony that we claim the foregoing as our own, we affix our signatures.

NICHOLAS BARRY.
CLYDE ALLEN.
